UNITED STATES PATENT OFFICE.

SIDNEY ROBERT HOLICK, OF LONDON, AND SYDNEY THOMPSON, OF MANCHESTER, ENGLAND.

APPARATUS FOR PRINTING UPON HOLLOW CYLINDRICAL AND LIKE ARTICLES.

1,176,449.

Specification of Letters Patent.

Patented Mar. 21, 1916.

Application filed April 25, 1914. Serial No. 834,289.

To all whom it may concern:

Be it known that we, SIDNEY ROBERT HOLICK, a subject of the King of Great Britain and Ireland, and a resident of London, England, and SYDNEY THOMPSON, a subject of the King of Great Britain and Ireland, and a resident of Manchester, England, have invented new and useful Improvements in Apparatus for Printing upon Hollow Cylindrical and like Articles, of which the following is a specification.

This invention relates to improvements in apparatus for printing upon the exterior surfaces of hollow cylindrical or other round articles such for example as the empty shells or cases of shot cartridges. It is in connection with the printing of such shells that the apparatus will be described, and from this description will be understood how other hollow articles than such shells may be similarly printed.

The type of apparatus to which these improvements relate is that comprising a face plate, disk, or the like provided with a series of spindles or studs arranged concentrically around the axis of the face plate and projecting from such face plate at equal distances apart with their axes parallel to each other and to the axis of the face plate.

The shells to be printed are placed upon the spindles and the face plate is intermittently moved angularly so as to bring each of the shells in turn to a point where each is printed upon by a printing cylinder. Suitable devices are employed for putting the shells on to the spindles and for removing or "extracting" the printed shells from the spindles after printing.

In carrying this invention into effect the face plate has combined with it positive driving means by which the spindles carrying the shells are constantly positively rotated around their axes and are quite independent of any rotary motion which is frictionally imparted to the shells by contact with the rotating printing cylinder. The spindles are so driven that when the face plate is not rotating the shells carried by the spindles have a surface speed equal to the surface speed of the printing cylinder. In fact each spindle and the shell tightly fitting upon it forms at the moment

of printing a positively driven impression cylinder of a printing machine.

The accompanying drawings illustrate the essential parts according to this invention of a machine for printing upon cartridge shells.

Figure 1 illustrates such a machine in end view. Fig. 2 shows it in front view. Fig. 3 is a rear end view to a larger scale of the face plate and coöperating parts. Figs. 4, 5 and 6 are views of details in the extracting mechanism by which printed shells are withdrawn from their rotating spindles.

A is a face plate or disk disposed to have angular movement around a horizontal axis. From its face project six rotatable spindles or supports B, B¹, B², disposed concentrically around the axis of the plate A at equal distances apart and with their axes parallel to each other and to the axis of the plate A. Secured to the same shaft as that to which the face plate is keyed is a toothed detent or ratchet wheel C. Combined with such wheel is a pawl D fixed on an angularly movable arm E which is adapted to be oscillated from a crank pin F on a wheel G through the medium of a connecting rod H. The wheel G is driven by a pinion G¹ on the first motion shaft. Each oscillation of the movable arm moves the wheel C and the face plate A through an angle of 60°. The different members are so relatively placed that each movement of the face plate results in its coming to rest with one of its spindles B opposite to the small printing cylinder J, another opposite to a device X by which a shell is put on to a spindle, and another opposite to a device Y by means of which the printed shells are in turn removed or extracted from the spindles. The shells fit with sufficient tightness on their spindles to be carried around by them and the outer surface of a shell forms a cylinder which is of the proper diameter to be brought into proper printing coöperation with the printing cylinder.

K is a fixed bracket to which one end of a band K¹ is secured. This band passes over a groove in the face plate A. The other end of the band is adjustably secured at K². This band or belt (the tension of which can be adjusted at K²) acts as a brake to keep

the face plate properly in the place to which it is moved by the ratchet and to maintain it at rest until the ratchet in its next movement imparts another angular movement to it. Any other suitable device may be provided to similarly hold the face plate in its position of rest.

M is a chute by means of which the shells are fed to the machine.

- 10 N is a feed wheel or drum which has an intermittent motion corresponding to the intermittent motion of the face plate A. It is driven from the face plate shaft by the chain N¹, and is provided with six longitudinal grooves in its circumference. Each of these grooves can take up a shell from the chute and carry it away from such chute.
- 15 O is a ram or plunger device by means of which shells carried by the feed wheel N from the chute are forced into place on a spindle B. The required reciprocal motion is given to the plunger through a rack P, wheel Q, crank pin R thereon, connecting rod S, hinged arm T and cam U, the result of their operations being that the wheel Q has angular motion imparted to it alternately in opposite directions and reciprocates the plunger O.

30 The printing roller or form cylinder J is continuously driven in any suitable manner and its direction of rotation and its disposition is such that it properly rolls in printing contact with each shell presented to it.

35 The ends of the spindles B which project behind the face plate A are each provided with a pinion b gearing with a wheel V which is loosely carried upon and so as to rotate around the shaft which carries the face plate A. The wheel V is constantly 40 driven from the first motion shaft through the pinion W. The result of gearing with the wheel V the spindle pinions b, is that the spindles B are constantly rotated by the wheel V. They rotate at a different speed 45 when the face plate is being turned than they do when the face plate is stationary, but the speed imparted to the spindles when the face plate is stationary is the proper printing speed for the printing cylinder 50 with which the shells carried by them coöperate.

The operation of the machine as far as feeding the cartridges on to the spindles and printing them is as follows: The feed wheel

- 5 N moves and stops in the same manner and at the same time as the face plate A. When in the stopped position shown in Fig. 1 the feed wheel N receives in one of its gaps or grooves a shell from the bottom of the 10 chute M. The wheel N then has angular motion of 60° imparted to it and carries the shell around to the position indicated at 1 in Fig. 1, where it again comes to rest. The shell carried by the feed wheel N is now 15 opposite to the end of one of the spindles

B⁵ (see Fig. 2) and it is now forced on to such spindle by the plunger O which moves inward through the gap in the feed wheel and forces the shell home on its spindle and then quickly retires and disengages itself 70 from the feed wheel. As soon as this is effected the feed wheel and the face plate move through an angle of 60° and again stop. The spindle carrying the shell is now in the position indicated at 2 in Fig. 1; the feed wheel has taken up another shell in its following groove and has brought such shell to the position 1 where another spindle of the face plate is in readiness to receive it and has it thrust upon it. After this has 80 been done the feed wheel and the face plate have another angular motion of 60° imparted to them. The first spindle which received a shell now comes to the position 3 and while the face plate is at rest it rotates in 85 printing contact with the printing cylinder J. Each successive spindle as it now arrives at the position 3 brings with it a shell for printing, the feeding operation being repeated with each spindle as it comes to position 1. After further successive moves of 60° the printed shells arrive at the position indicated at Y in Fig. 1 where the extractor, more closely shown in Figs. 4, 5 and 6, comes into operation and removes the shells 90 from their spindles when they halt at such position Y and drops them into a chute which conveys them to a slowly revolving tray Z.

95 The printing or form cylinder J has a gap J' longitudinally formed along it which comes opposite to the shell which is to be printed when such shell moves to its printing position. Further rotation of the form cylinder when the shell is in place and the face plate is at rest brings the printing matter or type into contact with the rotating shell. The impression being effected the gap J' again comes opposite to the shell, and while such gap is opposite to it and the shell 105 is thus out of contact with the form cylinder the next angular movement is given to the face plate.

110 The apparatus for withdrawing the printed shells from the spindles (herein generally referred to as "extracting" apparatus) is situated at the point Y in Fig. 1 and its construction is illustrated in that figure and in Figs. 4, 5 and 6.

115 Situated in prolongation of the axis of a spindle which is situated at the point Y when the face plate A is at rest, is a slide 8 which can reciprocate in a path in prolongation of such axis. This slide is shown in end view in Figs. 1 and 4, in side elevation in Fig. 5 and in view from underneath in Fig. 6. The slide 8 reciprocates in a bracket 9. It is reciprocated by a lever 10 and a link 11 which are operated through a pin x extending from the lever 10 to a cam 120

groove in the face of the disk 12. The slide is provided with two hinged jaws 13 provided with a spring 14 attached to their tails. This spring tends to keep the jaws

5 open.

15 is a slide with a wedge shaped end moving on slide 8. It can be moved to the position shown in Fig. 6 with its tapered end engaging with the tails of the jaws to close

10 such jaws and keep them closed, by means of the spring 16, angle lever 17, and pin 18 which engages the sliding wedge with a slot in the angle lever. By means of the angle lever 17 and pin 18 the sliding wedge

15 can be moved to the right of the position shown in Fig. 6 in order to disengage its end from the tails of the jaws and permit the jaws to open. The angle lever 17 is operated by means of a movable plate 19

20 which is brought up against or removed from the bowl 20 on the end of the lever 17. When the plate 19 is pressed sufficiently against the bowl 20 the sliding wedge 15 is withdrawn from the jaws and such jaws

25 are open.

It is while the plate 19 is pressing the bowl 20 that the slide 8 completes its inward motion until its open jaws come over the end of a printed cartridge shell. The plate

30 19 then moves away from the bowl 20 and permits the spring 16 to force the sliding wedge 15 into engagement with the jaws and close them upon the end of a cartridge shell. This is shown in Fig. 6. The slide

35 8 now commences its return movement to draw the printed shell from its spindle. After this withdrawal has been effected plate 19 again moves up to the bowl 20 and moves the wedge 15 to effect the opening of

40 the jaws to release the shell. The movements are then repeated. The plate is brought into and out of engagement with the bowl 20 by means of a lever 21 operated from a cam plate 22. See Fig. 1.

45 It is evident of course that the face plate or disk may be provided with any other suitable number of spindles for carrying the shells than six, and that in connection with any other such suitable number the operations of placing a shell on a spindle at

50 one rest, of printing such shell at the next or a subsequent rest, and of subsequently extracting such printed shell from its spindle may be effected.

55 What we claim is:

1. In a machine for printing on cylindrical shells, the combination of a disk, means for intermittently revolving such disk, a plurality of concentrically arranged

60 equidistant spindles on such disk adapted to carry the shells, means for positively and constantly rotating said spindles, a continuously rotated printing roller to which the

shells are successively presented, a longitudinal gap in such roller, the roller being so 65 timed that the shell is put in position and withdrawn without smudging, means for putting the shells on the said spindles and means for ejecting them after printing, substantially as described.

2. In a machine for printing on cylindrical shells the combination of a disk, means for intermittently revolving such disk, a plurality of concentrically arranged equidistant spindles on such disk adapted to 70 carry the shells, means for positively and constantly rotating said spindles, a continuously rotated printing roller to which the shells are successively presented, a longitudinal gap in such roller, the roller being so 75 timed that the shell is put in position and withdrawn without smudging, a feed drum for the shells, longitudinal pockets in such feed drum, a chute adapted to supply shells to the said pockets, means for intermittently 80 revolving the said drum to bring the shell opposite a carrier spindle, a plunger to force the shell on the spindle and means for ejecting the shell after printing, substantially as described.

3. In a machine for printing on cylindrical shells the combination of a disk, means for intermittently revolving such disk, a plurality of concentrically arranged equidistant spindles on such disk adapted to 90 carry the shells, means for positively and constantly rotating said spindles, a continuously rotated printing roller to which the shells are successively presented, a longitudinal gap in such roller, the roller being so 95 timed that the shell is put in position and withdrawn without smudging, a feed drum for the shells, longitudinal pockets in such feed drum, a chute adapted to supply shells to the said pockets, means for intermittently revolving the said drum to bring the shell opposite a carrier spindle, a plunger to force the shell upon the spindle, a shell ejecting device comprising a slide adapted to be reciprocated, spring opened 100 105 jaws upon such slide, a wedge adapted to close said jaws upon the shell, and means for withdrawing said wedge, substantially as described.

And in witness whereof we have hereunto 110 set our hands in the presence of two subscribing witnesses.
